INSTRUMENT CASE FOR A CHART RECORDER

William P. Godley, Maple Glen, Pa., assignor to Minneapolis-Honeywell Regulator Company, Minneapolis, Minn., a corporation of Delaware

Continuation of design applications Ser. No. 61,854 and Ser. No. 61,855, Aug. 23, 1960. This application Sept. 14, 1961, Ser. No. 66,856

Term of patent 14 years

(Cl. D52—6)

Fig. 1

Fig. 2

FIG. 1 is a perspective view of an instrument case for a chart recorder embodying my new design and showing the strip chart type.

FIG. 2 is a modified form of the instrument case disclosed in FIG. 1 and showing a circular chart type.

The bottom, not shown, is identical with the top, and the left side, not shown, is identical with the right side.

The rear, not shown, is flat and unornamented.

This application is a continuation of my two copending applications, Serial Nos. D.61,854 and D.61,855, filed August 23, 1960, now abandoned.

The ornamental design for an instrument case for a chart recorder, substantially as shown and described.
